Primary Examiner — Mark A Goodwin*Assistant Examiner* — Harold E Blackwell, II(74) *Attorney, Agent, or Firm* — Jose Cherson Weissbrot(57) **CLAIM**

The ornamental design for a support foot as shown and described.

DESCRIPTION

FIG. 1 is a top perspective view of a support foot showing my new design;

FIG. 2 is a bottom perspective view thereof;

FIG. 3 is a front elevational view thereof, the rear elevational view being a mirror image of FIG. 3;

FIG. 4 is a right side view thereof, the left side view being omitted, which forms no part of the claimed design;

FIG. 5 is a top plan view thereof; and,

FIG. 6 is a bottom plan view thereof.

The broken lines in the figures are for the purposes of illustrating portions of the support foot, which form no part of the claimed design.
